UNITED STATES PATENT OFFICE.

EARL P. ENGLEBEE, OF BOUND BROOK, NEW JERSEY.

MACHINE FOR CUTTING HOLES.

Application filed January 27, 1922. Serial No. 532,321.

This invention relates to pressure containers such as steam boilers and has for its more important objects to provide a novel form of hand hole cover and a machine for cutting or reaming hand holes adapted to receive such covers to form an effective seal. Other objects and advantages will appear as the invention is hereinafter disclosed.

Referring to the drawings, which illustrate what I now consider preferred forms of the invention—

Fig. 1 is a longitudinal sectional view taken on a plane including substantially the minor axis of the cutting or reaming machine.

Fig. 2 is a longitudinal view partly in section on a plane through the major axis of the machine.

Fig. 3 is a fragmentary detail view illustrating one of the elements shown in Figs. 1 and 2.

Fig. 4 is a section taken substantially on the line 4—4 of Fig. 2.

Fig. 5 is a section taken substantially on the line 5—5 of Fig. 2.

Fig. 6 is a section taken substantially on the line 6—6 of Fig. 1.

Fig. 7 is a detail view partly in section illustrating a different form of cutting tool.

Referring to the drawings, I have illustrated the header 10, of a steam boiler, which supports the boiler tubes, one of which is shown at 11. A second header 12 spaced from the header 10 and from the end of the tubes. Obviously, fluid under pressure will be contained in the tubes and in the space between the headers 10, 12. An opening or hand hole 13 is provided in the header 12 whereby access may be had to the interior of the tube 11 from the exterior of the boiler. I prefer to make these hand holes oval or elliptical in shape, although it will be understood that other shapes may be employed. A hand hole cover (not shown) is provided for each hand hole 13.

The opening 13 is tapering or outwardly converging and its shape and degree of taper are such that when the cover is inserted therein, a pressure-resisting and effective non-leaking seal of the hand hole is provided.

It will be noted that the effectiveness of

the seal will depend in a large measure upon the accuracy with which the hole 13 is cut or reamed. While other specifically different forms of machines may be employed for cutting or reaming the hand holes, I prefer at present to employ the machine shown in Figs. 1 to 6, since this machine may not only be employed to shape the hand holes before the boiler is assembled but also after the boiler is assembled. This machine may be constructed substantially as follows.

One or more, in the present case four, tool holders 16 are mounted for revolution about the longitudinal axis of the machine, and for radial movement with respect to said axis. This mounting may be effected by constructing each tool holder 16 in the form of a rectangular hollow prism, as shown, and slidably mounting each of the same in a corresponding one of the openings 17 of the four arm carriage 18. The latter has a hub portion 19 to which a gear 20 is secured. The gear 20 meshes with and is adapted to be driven by a pinion 21 secured to a shaft 22, suitably journaled in a bearing 24. The shaft 22 also has secured thereto a gear 23 which is adapted to be coupled to and driven by any suitable driving means or source of power, not shown.

Each of the tool holders 16 is adapted to receive a cutting tool 25 which may be adjusted radially by means of adjusting screws 26, each screwed into the base of a corresponding one of the tool holders. And each of the cutting tools may be releasably held in adjusted radial position, with respect to its respective tool holder, by virtue of the set screws 27.

Means are provided for causing the tool holders 16 to pursue such a path in their revolution as to cause the tools 25 to cut or form the desired shape of hole. In the present illustration the tool holders are to move in an oval or elliptical path or orbit and the means for causing them to pursue such path may be constructed substantially as follows.

A pair of relatively stationary cams 28 are provided. These cams are each generally elliptical in shape as shown in Fig. 5. Each of the tool holders 16 has secured thereto a pair of longitudinally and oppositely extending shafts 29, upon each of which a roll-

er 30 is mounted. The rollers 30 are each adapted to engage the periphery of one or the other of the cams 28. Closed helical springs 31 surrounding the group of four shafts 29 and seated in suitable grooves in the same, as shown, serve to maintain or aid in maintaining the rollers 30 in contact with the cams 28. By virtue of the structure thus far described, assuming that the cams 28 are held stationary, revolution of the carriage 18 will cause the tools 25 to pursue a path (illustrated in dotted lines in Fig. 4) corresponding to the desired shape of hand hole.

I also provide means for moving the tool holders 16, and the tools 25 carried thereby, radially while they are being revolved. I prefer to effect this movement by movement of the cams 28 toward and away from each other and to provide means for so moving the cams. The peripheries of the cams 28 are each shown as converging in an axial direction and each converging in a direction opposite to that of the other. In other words, in the present illustration, the peripheries of the cams are, generally speaking, frustums of elliptical cones with their smaller bases toward each other. Speaking more accurately, the peripheral surface of each cam is that generated by a line inclined with respect to the longitudinal axis of the machine and so moving as always to lie in the plane of the said axis and always to be in contact with what may be termed the pitch line of the cam. The rollers 30 are correspondingly shaped, i. e., each roller is a frustum of a circular right cone so designed that, in its orbital movement, it will always engage the periphery of a corresponding one of the cams 28 by a line contact. The cams 28 are permitted to move axially with relation to each other but are constrained against relative rotation with respect to each other by virtue of the laterally extending tongues 35, provided on one of said cams and extending into corresponding notches 36 provided in the hub of the other cam. The means for moving the cams 28 axially toward and away from each other will now be described. The hollow hubs of each of the cams are internally screw-threaded to cooperate with the screw threads 38, 39 provided on the exterior of a cylindrical member 40. One of the sets of threads 38, 39, and its cooperating threads on the corresponding cam hub, are right handed threads, while the other and its cooperating threads on the other cam hub are left handed (see Fig. 3). A hand wheel or other suitable operating member 41 is provided upon the member 40 for rotating the latter with respect to the cams 28. By turning the hand wheel 41 with respect to the cams 28, in one direction or the other, the cams

will be caused to approach or move away from each other, dependent upon the direction of rotation of the hand wheel. Obviously, when the cams 28 approach each other, the tool holders 16 and tools carried thereby are forced radially outward and when the cams move away from each other, the springs 31 cause the tool holders and tools to move radially inward.

Means are provided for positioning the machine with respect to the work piece and for releasably holding it in such position. Before describing the form of such means now preferred I wish to describe the operation of the machine when cutting tools of the general type shown at 25^a in Fig. 7 are employed. Let it therefore be assumed (it will hereinafter positively be disclosed) that means are provided for correctly positioning the machine in a roughed out opening 13 in the work piece, and for holding the machine in such position, so that the cams 28 will be constrained against rotation, and against axial movement except by manipulation of the hand wheel 41. The carriage 18 is rotated, as previously described, and the hand wheel 41 so turned as to cause the tools 25^a to engage and cut or ream the peripheral face of the hole 13. While revolving the cut by the tools may be deepened by turning the hand wheel in the proper direction, at the proper times, until the desired shape of hand hole is attained. The cutting tools 25^a may then be retracted, by reverse operation of the hand wheel 41 the machine stopped, and removed from the finished opening 13.

Instead of employing the flat edged tools 25^a it may be preferable to employ comparatively pointed tools such as those shown at 25 in Figs. 1, 2 and 4. For this purpose means are provided simultaneously to move the cutting tools radially and axially to effect the desired cut. One form of such means, together with a form of means for positioning and holding the machine in correct position, are shown in Figs. 1, 2 and 6, and may be constructed substantially as follows.

The member 40 is constructed in the form of a sleeve and is rotatably and slidably mounted upon a rod 45 having at one end a tapered thread 46 and at the other a nut 47, for a purpose hereinafter disclosed. A sleeve or tubular member 48 is slidably and rotatably adjustable upon the rod 45 and may be releasably held in adjusted position by means of a set screw 51. It will be noted that the sleeve is exteriorly screw-threaded to cooperate with the internal threads of the sleeve or hub of a hand wheel 50, these cooperating screw threads being designated 49. The hub of the wheel 50 extends into the hollow hub of the wheel 41,

these two wheels being relatively rotatable but constrained against relative axial movement by any suitable means such as a co-operating key or pin 52 and key way or annular slot 53. When the machine is to be employed for the purpose set forth above, the following positioning and supporting means may be employed.

A plurality of, in the instant illustration four, sectors 55 are provided. These are of such shape and design as to form a disk insertable into the tube 11, when the sectors are in inner radial positions, and to grip the inner face of the tube tightly when the said sectors are forced radially outward. Dowel pins 56 and cooperating pin receiving slots or openings 57 may be provided upon the sectors to hold or aid in holding the latter in assembled position. The disk formed by the sectors 55 is provided with a central, internally threaded, tapered opening 58 adapted to receive the screw-threaded end 46 of the rod 45. The design is such that upon rotation of the rod 45, in one direction or the other, the sectors 55 will be forced radially outward or permitted to move radially inward, depending upon the direction of said rod. Each of the sectors 55 is shown provided with a radial slot 59 adapted to receive the shank of a corresponding one of a plurality of bolts 60, these bolts being adapted to screw into suitably tapped openings in the left hand cam 28. The various sectors 55 are biased to inner radial positions by means of a spring band 65 mounted in a peripheral groove 66 in said sectors.

The design of the threads 38, 39 and 49 and of the rollers and peripheries of cams 28, is such that when the wheels 41 and 50 are rotated in unison the tools 25 will be moved radially and axially in such proportionate amounts as to effect the desired slope of cut in the bounding face or periphery of the hand hole. Releasable means are provided for causing either of the hand wheels 41 and 50 to rotate in unison with the other upon actuation of either of said wheels. This means may assume the form of a manually releasable pin 75 slidably mounted in a suitable opening in the hub or web of the hand wheel 41 and biased toward the other hand wheel 50 by a compression spring 76. The end 77 of the pin is adapted to enter any one of an annular series of holes provided in the web of the hand wheel 50 so that the two hand wheels may be releasably locked together in various positions of adjustment. The machine shown in Figs. 1 to 6 is designed to operate substantially as follows.

The machine, including the sectors 55 and bolts 60, is inserted through the hole 13 to be cut or reamed, after the tool holders 16 and sectors 55 have been set to their in-

nermost radial positions. The disk-forming sectors 55 are inserted into the tube 11. The machine is then bodily turned about its longitudinal axis until the major axes of the cams 28 lie in the plane of the major axis of the desired final form of hand hole. The nut 47 is then turned to cause the threaded end 46 of the rod 45 to spread the sectors 55 and to cause them to grip the inner surface of the tube firmly and securely. The machine is now correctly centered and positioned and will be effectively held in such position. It will be noted that the bolts 60 now prevent any rotation of the cams 28. The set screw 51 may then be backed off, the entire structure supported by the rod 45 moved axially to adjust the plane of the cutting tools generally at the desired position, and the set screw 51 tightened. By this operation the tools may be caused to assume the position substantially as shown in Fig. 1. The carriage 18 is now rotated in the proper direction by the driving means including gears 20, 21 and 23, the pin 75 retracted, and the hand wheel 41 rotated to adjust the tools 25 radially for the desired depth of cut. (The hand wheel 50 is held stationary during this last described adjustment.) The pin 75 is now released and entered into the nearest hole 78 to lock the hand wheels 41 and 50 together. Upon manual rotation of either hand wheel in the proper direction, both of the hand wheels will rotate in unison to force the cutting tools 25 radially outward, and simultaneously to move them axially by virtue of the threads 49. The desired sloping cut is thereby effected. After the first cut, any subsequent cut including the final one may be effected in a manner now obvious in view of the foregoing description.

After the hand hole is finished the rotation of the carriage 18 is stopped, the pin 75 is retracted, the tools are moved radially inward by means of the wheel 41, the nut 47 is turned to unscrew the end 46 of the rod 45 and the machine is removed from the work.

In accordance with the provisions of the patent statutes, I have herein described the principles of operation of my invention, together with the apparatus which I now consider to represent the best embodiments thereof, but I desire to have it understood that the apparatus disclosed is only illustrative and that the invention can be carried out by other means. Also while it is designed to use the various features and elements in the combinations and relations described, some of these may be altered and others omitted without interfering with the more general results outlined, and the invention, within the scope of the appended claims, extends to such use.

What I claim is—

A machine for cutting hand holes in plates and comprising in combination, a tool holder, means for revolving said tool holder, means including two cams for causing said tool holder to pursue a predetermined path in its revolution, means for moving said

cams toward each other, and means for causing said tool holder to move in a radial direction by movement of said cams toward each other.

In testimony whereof I hereto affix my signature.

EARL P. ENGLESBE.
